UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

SPINNING-SPINDLE.

SPECIFICATION forming part of Letters Patent No. 729,221, dated May 26, 1903.

Application filed February 14, 1903. Serial No. 143,393. (No model.)

To all whom it may concern:

Be it known that I, ALONZO E. RHOADES, a citizen of the United States, and a resident of Hopedale, county of Worcester, State of Massachusetts, have invented an Improvement in Spinning-Spindles, of which the following description, in connection with the accompanying drawings, is a specification, like letters on the drawings representing like parts.

10 This invention has for its object the production of simple and efficient means for equalizing the strain on a spindle-base when the nut is applied thereto to retain it on the spindle-rail, even when the longitudinal axis of the base is not at right angles thereto.

In order to make the longitudinal axis of the spindle vertical, it is often necessary to have the bottom of the spindle-base at an angle to the rail, this presupposing, of course, that the 20 rail is not truly horizontal. This leveling of the spindle-base is usually accomplished by inserting paper, cardboard, or a thin shim under the edge thereof, which must be elevated, and this cants the depending threaded 25 end or shank of the base relatively to the rail so that the latter will not be engaged squarely by the retaining-nut when screwed up on the shank, but will be inclined thereto. When the nut is set up, the strain is brought 30 upon one side of the casting forming the spindle-base, tending to weaken it and frequently resulting in breakage. By my present invention this inequality of the strain upon the base is avoided, even though the latter is set 35 at quite an inclination relatively to the rail.

The various novel features of my invention will be described hereinafter and particularly pointed out in the claims.

Figure 1 is a side elevation of a spindle-base 40 and part of a spindle, the base being secured to the rail and with one embodiment of my invention illustrated in use. Fig. 2 is a partial sectional detail showing the slope of the spindle-rail exaggerated, to more clearly indicate the manner in which unequal strain upon 45 the base is obviated; and Fig. 3 is a diametral section of the retaining-nut and the equalizing-collar, with which it co-operates.

Referring to Fig. 1, the spindle S, broken off 50 to save space; the spindle-base B, enlarged at B' to rest upon the spindle-rail R, and having

an externally-threaded shank B² to extend through the rail, may be and are of any well-known or usual construction.

In Fig. 2 I have shown a shim s^x inserted 55 beneath the enlargement of the base, at one side thereof, to level the spindle-base and bring the longitudinal axis thereof into vertical position, because of the inclination of the spindle-rail R, though paper, cardboard, or 60 any other leveling means, screws, or other means may be employed, all being well known. When thus leveled, the shank B² is not at right angles to the rail and the ordinary retaining-nut would, if used, bear at only 65 one side against the rail, and thereby subject the spindle-base to unequal strain. To obviate this objection, I make in the end of the retaining-nut n nearer the rail a rounded 70 socket or concavity, as n^x, and from the nature of the case this socket will be annular and concave in cross-section, as shown in Figs. 2 and 3. An equalizing member (shown as a ring e^x) is adapted to loosely surround the shank of the spindle-base between the 75 rail and the nut, the face e of said equalizing member to contact with the rail being flat, while its opposite face e' is convexed or rounded on the same curvature as the socket of the nut. This face e' will be annular and 80 convex in cross-section, manifestly, and when the nut is set up the convex face of the equalizing member enters and is seated in the socket n^x of the nut, thus forming a species of ball-and-socket connection or knuckle- 85 joint between nut and ring. Even if the base is leveled up so that its longitudinal axis is not at right angles to the spindle-rail, as shown in Fig. 2, it will be manifest that when the nut is set up the pressure on the 90 base will be equalized through the co-operation of the nut and equalizing member. On the other hand, if the latter member be omitted and the usual nut be employed the latter 95 will not rest squarely against the rail, and the strain will be brought on one side of the spindle-base.

The inclination of the rail is exaggerated in Fig. 2 to more clearly show the operation and effect of my invention.

As the socket in the nut and the convex face of the equalizing member are sections of

spheres of like radius, it will be seen that the spindle-base may be leveled in any direction without causing unequal strain on the base when the nut is set up.

5 Having fully described my invention, what I claim as new, and desire to secure by Letters Patent, is—

1. A spindle-base having a threaded shank to extend through the rail, a retaining-nut o screwed onto the shank and having an annular socket in its top, and an equalizing-collar having a flat face to bear against the bottom of the rail and an opposite, annular convex face to fit the socket in the nut.

15 2. A spindle-base having a threaded shank to extend through the rail, a retaining-nut screwed onto the shank, and having a rounded socket in one end, and an equalizing-collar loosely surrounding the shank between the

rail and nut, said collar having a flat face to 20 bear squarely upon the rail, and an opposite rounded face to enter and fit squarely the socket in the adjacent end of the nut.

3. A spindle-base having a threaded shank to extend through the rail, a retaining-nut 25 adapted to be screwed onto the shank and having a rounded socket in its upper end, and an equalizing-collar having a flat face to rest squarely against the bottom of the rail, and a rounded, opposite face to enter and be seated 30 in the socket.

In testimony whereof I have signed my name to this specification in the presence of two subscribing witnesses.

ALONZO E. RHOADES.
